(57) **CLAIM**

The ornamental design for an ophthalmic device for mapping the acuity of a human eye using wavefront analysis, as shown.

DESCRIPTION

FIG. 1 is a perspective view of the ophthalmic device for mapping the acuity of a human eye using wavefront analysis, in accordance with the present invention;

FIG. 2 is a front elevational view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
